Inventor:
Frank C. De Reamer,

His Attorney.

COMBINATION CONTACT DEVICE.

Application filed October 21, 1921. Serial No. 509,344.

To all whom it may concern:

Be it known that I, FRANK C. DE REAMER, a citizen of the United States, residing at Bridgeport, in the county of Fairfield, State of Connecticut, have invented 5 certain new and useful Improvements in Combination Contact Devices, of which the following is a specification.

There are on the market, broadly speaking, 10 three kinds of attachment plug caps, one having parallel blades thru which the electrical circuit is established, the second, tandem blades, and the third, a combination of the two preceding types.

15 It is highly desirable that the receptacles which are to receive these caps shall be of such a character that the different caps can be used interchangeably. Owing to the fact that the blades in different types of caps 20 occupy planes at right angles to each other, and to the further fact that the receiving devices are necessarily small, the problem is to devise suitable fixed contact devices or clips which will receive all of said types of 25 blades with equal facility, which will not work loose, which will afford ample contact surfaces to establish the proper circuit connections and which will have long life in service.

30 The object of the present invention is to improve the construction of fixed contacts or clips for attachment plug cap receptacles.

For a consideration of what I believe to be novel and my invention, attention is directed to the accompanying description and 35 claims appended thereto.

In the drawing, which is illustrative of one of the embodiments of my invention, 40 Fig. 1 is a perspective view of a wall receptacle adapted to receive an attachment plug cap having tandem blades or parallel blades or a combination of such blades; Fig. 2 is a perspective view of an attachment plug cap having tandem blades; Fig. 3 is a similar 45 view of a cap having parallel blades; Fig. 4 is a perspective view of an attachment plug which is itself adapted to be screwed into a lamp socket or other receptacle and is capable of receiving caps of different types; 50 Fig. 5 is a sectional view of a receptacle showing the arrangement of my improved contact device or clip therein; Fig. 6 is a plan view of the same, the upper half of the receptacle being removed; Fig. 7 is a perspective view of a contact device or clip and

also of parts of tandem and parallel blades, and Fig. 8 is a plan view of the sheet metal blank from which the contact device is made, the last two figures being on a greatly enlarged scale for the purposes of illustration. 60

9 indicates the base portion of a receptacle which may be made in any suitable manner. 10 indicates the insulating top or removable portion, the latter being provided with two opposed T-shaped openings 11. 65 The walls of the openings are slightly larger than the blades on the attachment plug caps and preferably the fixed contacts or clips are located below the front surface or face so as to prevent danger to a person from 70 electrical shocks and also to prevent improper connections. The vertical parts of the T slots are arranged to receive the tandem blades, and the horizontal, the parallel blades. The construction also permits the 75 use of a combination plug cap which has one blade of the so-called tandem type and one of the so-called parallel type, as will be readily understood.

The removable part in addition to forming a flat seat for the attachment plug cap is provided with screw terminals 12 and 13 to which the line conductors are fastened. The said part is also provided with slotted 80 clips 14 (only one being shown), by means of which the receptacle can be mounted in an outlet or junction box.

In Fig. 2 is shown an insulating cap 15 having two blades 16 arranged in tandem, each blade being provided with a bent-over 85 end and a screw 17 to connect it to one part of a current carrying cable. The cable or cord is admitted to the cap thru the hole 18. The cap shown in Fig. 3 is similar to the 90 one shown in Fig. 2 except that the blades 16^a are arranged in parallel. To prevent the small strands of wire in the cord from getting in the path of the blades a thin sheet of insulation 19 may be slipped over 95 the blades and seated on the cap. In the case of the tandem blades each is provided with a small V-shaped notch 20 which engages a part of the fixed contact to form a locking device and also serves as a part of a seating means. In the case of the parallel 100 blades each is provided with a small opening 21 for the same purpose.

In Fig. 4 is shown a plug 22 that has a 105 screw threaded metal shell 23 and is adapted to be screwed into a lamp socket or other 110

corner, and a center terminal 22^a the other. The front face of the plug is made flat to form a seat for a cap and has double opposed T-shaped slots.

Referring now to the combination contact device or clip, it is desirable to make these as small as possible without, however, sacrificing the proper contact area necessary to carry the current without appreciable loss on the one hand or undue wear on the other. It is also important to reduce the number of parts to the minimum and avoid joints. To meet these conditions the contact is formed of a single sheet metal blank and without joints. The blank can advantageously be made of spring material such as phosphor bronze. The blank is of the shape illustrated in Fig. 8 and is formed by a blanking die, that is to say, it has three arms, 25, 26 and 27 which are united at their inner ends. The arm 25 is made somewhat wider than the others because an inner end portion of it forms the base of the finished clip. The arms 26 and 27 are each provided with a rounded locking projection 28 which projections lie in the plane of the finger and engage either the V-shaped notch 20 in the cap of Fig. 2 or the small hole 21 of the cap of Fig. 3, and are preferably so positioned that they exert pressure on the blades in a direction tending to move the cap toward its seat. At the junction or base of the arms is formed a hole through which the clip retaining screw passes. Each arm of the blank is first bent by a die operation to give it the offset 29, as shown in Fig. 7, and also the slightly out-turned end 30. They are then folded or bent along the points indicated by the dotted lines, Fig. 8, to form contact fingers, the resulting structure being illustrated in Fig. 7; that is to say, the clip has a base and three contact fingers all extending at right angles to the base and therefore in the same general direction. The offsets are shaped to engage the flat sides of the blades and are of sufficient area to ensure good contact. By forming the blank in the manner illustrated it becomes a very simple operation to first form said offsets and then bend the arms to the desired shape. The fingers 25 and 27 occupy parallel planes while the finger 26 occupies a plane which is perpendicular to those of the other fingers. The clips when finished are mounted on their base or support, whether it be the one shown in Fig. 1 or Fig. 4, for example. Each is secured in place by a single screw 31 and a square nut 32, the latter being of such a size relative to the base of the clip that it is prevented from turning by the bases of the bent arms or fingers of the contact clip. This is of course, advantageous in assembling the structures.

the other to terminal 13 by the conductor 13^a, in the case of the construction shown in Fig. 1. In the case of the construction shown in Fig. 4 one clip is electrically connected to the screw shell 23 and the other to the central terminal 22^a.

On pushing the blades of the attachment cap of Fig. 2 into place in the receptacle each blade 16 is engaged by the contact fingers 26 and 27 and the rounded locking projection 28 on the finger 27 enters the V-shaped notch 20 in the blade from the side and prevents the blade from being accidentally displaced. It also aids in establishing the circuit connection because it is forced against the blade by the spring pressure of the finger itself. When the blades of the cap of Fig. 3 are pushed into place they pass between the fingers 25 and 27 of each clip and are also engaged by the edges of fingers 26, and the projection 28, thereon enter the holes 21 and lock the blades.

In accordance with the provisions of the patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:

1. In a plug receptacle, a contact member for receiving plug contact blades, said contact member comprising a rectangular base portion and three contact fingers integral therewith extending substantially perpendicularly therefrom in the same direction, each of said fingers joining the base at and along a separate edge thereof whereby two of said fingers lie in parallel planes with the remaining finger lying in a plane at right angles to said planes and a contact blade locking projection along and integral with each of two corresponding edges of two of said fingers, each of said projections lying in the plane of the finger with which it is integral.

2. In a plug receptacle, contact members for receiving plug contact blades, each of said contact members being formed from sheet metal and comprising a rectangular base portion and three contact fingers integral therewith extending substantially perpendicularly therefrom in the same direction, each of said fingers joining the base at and along a separate edge thereof whereby two of said fingers lie in parallel planes with the remaining finger lying in a plane at right angles to said planes, one of said fingers being wider than and over-

lying the two remaining fingers and said last-named fingers being each provided with an integral contact blade locking projection along one edge, which projection lies in the plane of the contact finger.

3. In a plug receptacle, contact members for receiving plug contact blades, each of said contact members being formed from sheet metal and comprising a rectangular base portion and three contact fingers integral with and joining the base portion each at and along a separate edge thereof, one of said fingers being of the same width as that portion of the base which it joins and extending outwardly from the base perpendicularly thereto, and the remaining contact fingers each being provided with offset bends between outer and inner end portions thereof, said end portions of each finger lying in planes perpendicular to the base portion and to the planes of corresponding portions of the other finger, each of said last-named contact fingers being provided with an integral contact blade locking projection along one edge, such edge of the one corresponding to such edge of the other and the projections lying in the planes of their respective fingers on the outer end portion of said fingers.
4. In a plug receptacle, a contact member for receiving plug contact blades which lie in planes at right angles to and intersecting each other, said contact member comprising a rectangular base portion having a central perforation, three contact fingers integral with the base portion, being formed therewith from a common sheet of metallic spring material and joining the base portion

each at a separate edge and side thereof, a first contact finger being substantially straight and extending outwardly from the base portion in a plane substantially perpendicular to the base portion, a second contact finger extending outwardly from the base portion in a plane substantially parallel with and adjacent that of the first contact finger and being provided with an offset between its base end and its outer end whereby an outer end portion lies more closely parallel with and adjacent the first contact finger than the remaining portion thereof, a third contact finger extending outwardly from the base portion in a plane substantially perpendicular thereto with a face adjacent and substantially parallel with the second contact finger and an edge adjacent and substantially parallel with the first contact finger, the third contact finger being provided with an offset between its base end and its outer end whereby an outer end portion lies more closely adjacent the second contact finger than the remaining portion thereof, a projecting blade locking means formed on an edge of and integral with the outer end portion of the second contact finger adjacent the third contact finger, and a projecting blade locking means formed on an edge of and integral with the outer end portion of the third contact finger adjacent the first contact finger, each of said locking means lying in the plane of that portion of the contact finger on which it is located.

In witness whereof, I have hereunto set my hand this 19th day of October, 1921.

FRANK C. DE REAMER.
